UNITED STATES PATENT OFFICE.

JOSIAH H. WILLIAMS, OF BALTIMORE, MARYLAND.

MOLD FOR MAKING GLASS SIGN PLATES.

Application filed May 4, 1923. Serial No. 636,669.

To all whom it may concern:

Be it known that I, JOSIAH H. WILLIAMS, a citizen of the United States, residing at Baltimore and State of Maryland, have invented new and useful Improvements in Molds for Making Glass Sign Plates, of which the following is a specification.

This invention relates to a mold for use in making glass sign plates of that kind adapted for use in illuminated signs, such plates consisting usually of rectangular or oblong rectangular glass sheets of plain, opalescent or prismatic glass bearing sign letters or characters in relief and designed to be properly assembled in a sign box or casing to produce the desired sign, a suitable light giving element or elements being placed behind the sign plates to cause the light to show therethrough and render the sign visible at night.

Sign plates of this character have heretofore been made either by press-molding the individual heat-softened plates, already formed of glass, between dies having surfaces to produce the sign character in relief thereon, or by applying pressure by means of a hand tool to portions of the softened glass overlying sunken character-forming surfaces of a die. Such plates so produced bear a sign letter, character or other device appearing in relief on its outer or front face and having a corresponding depression on its inner or rear face. These methods of manufacture require the use of sheet glass already formed and which must be heated and softened for the formation of the sign character therein, two separate manufacturing methods thus being necessary in making the sign plates from an original glass batch. Such methods of manufacture are, therefore, comparatively costly not only because of the two separate manufacturing processes referred to, but also because of the slowness of manufacture of the glass plates themselves and limited number which may be turned out in a given working period. An objection to the sign plates themselves produced by these methods is that, in the formation of the sign characters, the glass is stretched and relatively to the body of the plate, as a result of which the plates are liable to become easily cracked or broken in transportation or while being handled, or from expansion

and contraction, which, on account of the price at which the plates are sold, is an item of importance to shipping concerns, sign makers and others handling or using the product.

One object of my invention is to provide a mold wherein a large number of sign plates may be made in a single operation directly from the crude glass by the "blowing" process, whereby the steps of manufacture are simplified and reduced, and whereby a greater number of sign plate making operations may be performed within a given time and a larger number of sign plates made on each working operation, allowing such plates to be made with greater ease and facility, in greater quantities and at much less cost.

A further object of the invention is to provide a mold in which a multi-sided bottle may be blown, each side of which bottle forms one or more sign plates adapted to be separated by division of the sign bearing portions of the glass from each other, and in which the glass plates so produced are also so formed as to facilitate their separation from each other and to furnish plates which are of maximum strength and not liable to be easily broken or cracked.

A still further object of the invention is to provide a mold which, by reason of its construction, allows ready and convenient application and removal of interchangeable die plates for forming different sign characters, which is also adapted to be easily and quickly closed for use and opened for removal of a formed bottle, and which admits of the production of a maximum number of sign plates within a given working period.

With these and other objects in view, the invention consists of the features of construction, combination and arrangement of parts, hereinafter fully described and claimed, reference being had to the accompanying drawings, in which:—

Figure 1 is a front elevation of a mold embodying my invention, showing the same as it appears in closed condition.

Figure 2 is a side elevation of the same.

Figure 3 is a top plan view of the closed mold.

Figure 4 is a vertical section through the mold taken on line 4—4 of Figure 3.

Figure 5 is a vertical section through the mold taken on line 5—5 of Figure 3.

Figure 6 is a horizontal section on the line 6—6 of Figure 1.

5 Figure 7 is a similar view of the mold as opened to permit removal of the blown bottle.

10 Figure 8 is a vertical section through the bottle removed from the mold and as it appears before subdivision.

Figure 9 is a horizontal section on line 9—9 of Figure 8.

Figure 10 is a view of a completed double sign plate.

15 Figure 11 is a vertical section on line 11—11 of Figure 10.

In carrying my invention into practice I provide a mold comprising a base-plate 1 and a mold proper of circular or other suitable external outline shape mounted thereon and preferably divided on vertical lines to form three sections, to wit, a relatively stationary main or rear section 2 and two counterpart swinging sections 3 and 4.

20 These mold sections 2, 3 and 4 are provided at or near their meeting edges with hinge-knuckles or eyes 5 engaging supporting posts or rods 6 whereby the mold sections are hingedly connected to permit the sections 3 and 4 to be swung inwardly and outwardly for the purpose of opening and closing the mold body. The sections 3 and 4 are adapted to ride upon and to be supported by the base-plate at all points in their

35 open and closed positions. The posts or rods 6 are preferably fitted at their lower ends in slots 7 in the base-plate so as to allow them to be pushed straight back a distance when the mold sections 3 and 4 are 40 swung outwardly to the limit of their arcs of movement, in order to enable the mold to be opened full wide and shifted on the base-plate so as to allow the formed bottle, made as hereinafter described, to clear the

45 mold and to be freely and easily released and removed. A cover, consisting of two sections 8 and 9, is provided for closing the top of the mold body, and said cover sections 8 and 9 are provided at the rear thereof 50 with hinge-knuckles or eyes 10 engaging a pintle 11 on the rear mold body section 2, so as to adapt the said cover sections to be swung laterally to open and closed positions. The cover sections are shaped to

55 form a shoulder cavity 12 and neck opening 13, as shown. The free edges of the body sections 3 and 4 and cover sections 8 and 9 are provided with suitable operating handles 14, whereby they may be conveniently opened and closed, and suitable latches 15 are provided for cooperation with said handles for holding the mold body and cover sections securely connected in closed position. The abutting faces of the free

65 edges of the mold body and cover sections may also, if desired, be provided with dowel pins 16 and dowel seats 17 to guide them accurately into registering relationship.

The mold sections when closed form a mold chamber of any suitable angular form, 70 that is, having any suitable number of angularly related sides or surfaces, and in which, for the purposes of this invention, the number of angular sides or surfaces is exactly double that employed for the production of a given number of panels or sign plate molding sides. In the construction shown, for example, the mold chamber is dodecahedron shaped, being formed with six plate forming sides or surfaces 18, which are relatively wide and extend the full depth 75 of the mold chamber, and an equal number of narrower break-line-forming sides or surfaces 19 which are arranged between and intersect the surfaces 18 and also extend the full depth of the mold chamber. The sides 18 are recessed for their full width and depth to receive forming dies 20, the function of which is to form and impart the desired configuration to the sign plate producing sides of the bottle to be blown, while the well defined but considerably narrower sides 19 are designed and are so arranged with relation to the die faces as to produce thinned corner angles at the intersection or 80 points of juncture of such sign plate producing sides in order to facilitate and ensure a clean vertical separation of the sign plates from one another. While a mold with six sign plate forming sides and six 85 break joint producing sides is shown, it is to be understood that the invention is not in any manner limited thereto, as the number of such sides may be varied according to the size of the bottle to be blown and the 90 number of sign plate producing surfaces to be produced in a bottle of any given size.

Extending upwardly from the base-plate 1 is a central boss 21 preferably of circular outline and which constitutes the bottom of the mold chamber. This boss or mold bottom is provided with a recess 22 to receive a bottom die 23 adapted for forming one or more sign plate producing panels in the bottom of the blown glass bottle, thus enabling practically all portions of the bottle blown to be utilized in order to reduce waste of glass to the minimum. The lower edges of the mold sections 2, 3 and 4 are cut away to provide outer portions 24 which bear 100 upon the base-plate 1 and inner portions 25 which overlap the upper marginal surface of the boss 21 and adjacent portion of the upper face of the die 23, when the mold is closed, thus overlying and closing the joint 105 between the bottom 21 and die 23 against access of glass thereto from the mold chamber. If desired, the periphery of the boss 21 and inner faces of the portions 24 of the mold sections may be beveled or undercut 110

for lapping engagement when the mold sections are closed to form a tight joint and lock the mold sections against relative upward displacement. The mold, constructed as above described, is adapted for the formation in its chamber of a blown bottle conforming in shape and size to the shape and dimensions of the chamber, which bottle is designed to be subdivided to provide sign plates of definite shape and dimensions, as hereinafter described.

The dies 20 fit snugly and wholly within their receiving recesses in the sides 18 and are removably secured therein by screws or other proper fastenings 26. The inner faces of these dies at their lateral margins intersect the lateral margins of the sides 19, and hence said dies and sides 19 provide a bottle body forming surface which is continuous or without break, i. e., without inwardly jutting die projections, entirely around the same. The said inner face of each die is provided with sunken or depressed portions in the form of grooves 27 delineating one or more letters or whatever characters it is desired to produce in glass. Two or more die members bearing the same or different character forming grooves may be fitted, one above the other, in each recess, or a single die member, extending the full depth of the recess, may be fitted therein and such single die member may be provided with depressions for forming a single letter or character or two or more letters or characters. In the present instance, I have shown each die member 20 provided with two superposed letter or character forming impressions, adapting the same to form a glass panel composed of two superposed sign plates adapted to be separated from each other on a transverse line. The die member 23 has a flat upper forming face provided with one or more character forming depressions or grooves 27'. The die members 20 are of interchangeable type and are adapted to be slidably fitted within and removed from their receiving grooves when the cover sections 8 and 9 are swung to open position, and to permit of their ready insertion and extraction they are provided in their upper edges with undercut grooves or recesses 28 for engagement of suitable manipulating hooks or tongs therewith. The die member 23 is provided with similar tool receiving recesses 28' for the same purpose, which recesses 28' are normally covered by the mold sections 3 and 4 when in closed position and exposed when said mold sections are swung outwardly or opened.

In the operation of the device, dies for forming a hollow glass body or bottle, having the desired separable sign plates formed thereon, are fitted in the mold and the mold heated to the desired temperature. While

the mold is being heated the workman or glass-blower takes a batch of plastic glass upon the end of a blow-pipe and partially expands the same by blowing, after which the batch of glass is inserted in the mold chamber and the mold closed, the glass batch being suspended within the mold chamber from the end of the blow-pipe which extends through the neck opening 13 in the mold top or cover. The mold being closed, and the sections thereof locked firmly in assembled relation, the workman blows into the pipe so as to expand the plastic glass in all directions into bottle form, so that the glass entirely fills the interior of the mold and is pressed against the faces of the dies and the sides or surfaces 19 and within the character forming depressions 27 and 27'. A hollow body or bottle 29 is thus produced, having an annular series of angularly related sides or sign forming panels 30, formed by the dies 20, connecting webs 31 between the lateral edges of said panels, a bottom panel 32 formed by the bottom die 23, which is marginally connected with the lower edges of the panels 30 by webs 33, and a shoulder or top portion 34 terminating in a tubular extremity or neck 35. Upon the completion of this bottle blowing operation, the mold is opened and the bottle removed and subdivided for the separation and production of the component parts thereof forming individual sign plates.

An important part of my invention resides in the form and relative arrangement of the faces of the dies and the angular surfaces 19, whereby sign plates of a novel form and possessing meritorious features are produced, and whereby thinned break-line margins or joints between the individual side plates are produced, facilitating their separation from each other without liability of breakage. It will be observed that the faces of the die plates are plane or smooth-surfaced with the exception of the character delineating depressions therein, and that the centers of these die surfaces lie closer to the center of the mold chamber than their lateral margins, the distance between the axis of the mold chamber and the center of the die plate, and the lateral margins of said plate and the surfaces 19, gradually increasing on radial lines. As a result, each sign plate or panel 30 produced is thickest at its center, as indicated at 36, and, as its inner face is convexly curved, it gradually diminishes in thickness towards its marginal edges, where it is the thinnest, due to the gradual increase in outward expansion of the glass from the center line toward the marginal lines of each panel. The thin marginal portions of adjacent panels, which are thinnest at the web lines 31 formed by the surfaces 19, provide weakened break-line

portions adapting the lateral margins of the panels to be separated, by suitable glass breaking or "cracking" means, with a minimum amount of time and labor and without liability of breaking or otherwise injuring the panels. Where two or more superposed sign plates are formed by each panel made by one and the same die 20, the die is provided with a supplementary horizontal transverse groove or recess 37, into which the glass will be formed to provide a corresponding weakened break-line portion 38 between the sign plates on the panel. Similarly, depressions 39 are formed in the dies and mold surfaces at the angles of intersection of the bottle body forming portions and bottle bottom and top or shoulder forming portions, allowing the glass to expand to produce the weakened break-line portions 33 between the bottom panel 32 and lower edges of the sign panels and weakened portions 40 between the upper edges of the sign panels 30 and the shoulder 34.

In the operation of subdividing the bottle, the blowing tool is first cracked off the neck 35, after which the shoulder 34 is removed from the bottle body along the line 40, whereupon the remainder of the bottle may be separated along the weakened lines 30 through any prescribed course of procedure found in practice to be advisable according to the size of the bottle and number of subdivisions to be made. The construction described lends itself very well to the subdivision of the bottle, in a ready, quick and convenient manner, by means of an ordinary "cracking" process, in which a hot wire is laid along the line of separation to heat up the glass and then the glass is chilled in any suitable manner, with the result that it breaks along the previously heated line. This method will allow very clean cuts to be secured, but should any roughened surfaces be left upon the edges of the individual panels, these may be removed by grinding or otherwise. Where the bottom panel 32 is formed with a single letter, character, symbol or other device, it may, for special purposes, be allowed to remain in the substantially hexagonal form it is produced, or it may be trimmed down in any suitable manner to any prescribed size.

When each panel 30 forms two sign plates, the panels 30 may first be separated from each other along vertical lines, producing the double sign plate shown in Figures 10 and 11, after which each panel may be subdivided along the weakened break-line 38 to produce the individual panels 41.

A sign plate 41 produced according to my invention will be provided with an outer flat or plane display face 42 having the sign letter or character 43 in relief thereon, this face, which is formed directly by the smooth die face, being sufficiently smooth and

polished for use without further treatment. The inner or rear face of this die plate will be convexly curved vertically and transversely, usually to a greater degree in the transverse than in the vertical direction, 70 said plate being thickest at the center and thinning toward its margins and being smooth and having a finish similar to that of a fire-polish finish as a result of the blowing action described. Such construction, in 75 addition to providing the thin webs 31 between adjoining plates to facilitate their separation, ensures the reflection of the sign light from the rear from one letter to another and the radiation of the light rays 80 through the thin portions so as to give effective illumination to the letter or character in relief on the outer face of the sign plate. Such construction also provides a sign plate which, while not abnormally thick at any 85 point, and not abnormally thin at its margins, is thin enough at all points for efficient transmission of light while thick enough to withstand rough handling in service, without liability of cracking or breaking in 90 transit or while being handled, in which respect loss from breakage is considerably reduced over other sign plates of that character having sign characters which are in relief on their outer side and hollow on their 95 inner side and formed by stretching outwardly a portion of the body of glass, and which are therefore thinner and of less strength than the body of the plate itself. Furthermore, as the inner face of my glass 100 sign plate is polished and smooth-surfaced, it will, when installed in a sign, not readily retain dust and will allow dust collected to be readily washed off by rain water. My sign plate is thus advantageous in this respect over sign plates of the character heretofore produced which have more or less rough inner faces, due to their method of manufacture, allowing dust to collect and interfere with the transmission of light rays. 105 Hence by the mode of manufacture herein-described a glass sign plate may be produced which ensures long and satisfactory service and a reduction of waste caused by breakage.

By means of my improved mold, it will be seen that on each working operation a bottle capable of being subdivided to produce a plurality of sign plates will be made, allowing a very large number to be turned out from one and the same mold within a working day, ensuring production of such glass signs in a ready and convenient manner and at a comparatively low cost.

I am aware of the fact that it has here- 125 tofore been proposed to produce sign letters as such by blowing a multi-sided bottle in a mold, having a blow-chamber with forming sides corresponding in number to the sides of the bottle to be blown, such mold 130

- sides being provided with dies having acting surfaces of less dimensions than said mold sides and jutting inwardly therefrom, each die being designed to produce a glass 5 letter convex on its outer side and depressed or hollowed on its inner side, the glass sheet surrounding the letter being stretched to an extreme uniform thickness from all sides toward the margins of the letter in order 10 that the entire bottle side or panel produced may be broken away beyond the margins of the letter. The production of such sign letters as such, however, requires the use of a mold in which the glass is expanded outward 15 radially beyond the line of the character forming portion of the die in order to produce the uniformly thinned glass sheet referred to, in which respect such prior mold structure differs essentially from my 20 mold construction in which the dies are flush with the mold sides and operate to produce solid letters in relief upon a comparatively thick sheet of glass capable of use as a sign plate, for which obviously the prior 25 product mentioned is not adapted. Furthermore, with my construction the sign plate is solid at the center and thinned gradually toward its edges and is thinned to an easily-fracturable condition at its edges only. 30 Other important differences in the mold structures and products thereby produced will be apparent from the foregoing description setting forth in detail the characteristic features of my invention.
- 35 Having thus fully described my invention, I claim:—
1. A mold for blowing glass bottles having character bearing sides separable from each other to form sign plates, said mold 40 having a forming chamber provided with angularly related bottle side forming walls of a predetermined width and relatively narrower corner angle forming walls disposed between adjacent bottle side forming 45 walls and arranged at oblique angles there- 50 to, each bottle side forming wall being provided with a character molding die surface and a flat die surface extending beyond said character molding die surface to and intersecting adjacent corner angle forming walls.
- 55 2. A mold for blowing glass bottles having character bearing sides separable from each other to form sign plates, said mold having a forming chamber provided with angularly related bottle side forming walls of a predetermined width and relatively 60 narrower corner angle forming walls disposed between adjacent bottle side forming walls and arranged at oblique angles there- 65 to, each bottle side forming wall being provided with a sunken character molding die surface lying within the plane of said wall, and a flat die surface extending beyond said character molding die surface to and intersecting adjacent corner angle forming walls.
3. A mold for blowing glass bottles having character bearing sides separable from each other to form sign plates, said mold having a forming chamber provided with angularly related bottle side forming walls 70 of a predetermined width and relatively narrower corner angle forming walls disposed between adjacent bottle side forming walls and arranged at oblique angles there- 75 to, each bottle side forming wall being provided with a recess, and a die fitted in said recess and having a character delineating surface and a flat face extending at all sides beyond the margins of said character delineating surface and intersecting the corner 80 angle forming walls bounding the same.
4. A mold for blowing glass bottles having character bearing sides separable from each other to form sign plates, said mold having a forming chamber provided with 85 angularly related bottle side forming walls of a predetermined width and relatively narrower corner angle forming walls disposed between adjacent bottle side forming walls and arranged at oblique angles there- 90 to, each bottle side forming wall having a recess, and dies fitted in said recesses, each die being provided with a plurality of superposed character delineating surfaces and having a break-joint producing surface 95 between the character delineating surfaces thereof.
5. A mold having a forming chamber provided with an annular series of angularly related main forming walls and joint producing walls arranged between and lying at a greater radial distance from the axis of the chamber than said main forming walls, each main forming wall being provided with a recess, and a die fitted in said recess and 100 provided with superposed character delineating surfaces and break-joint producing recesses between adjacent surfaces.
- 105 6. A mold comprising a base plate having a recess, an openable and closable body mounted on said base plate and forming a mold chamber having angularly related sides, each provided with a recess, an openable and closable cover for said mold chamber, and removable character forming dies 110 mounted in the recesses of the base plate and sides of the mold body.
- 115 7. A mold comprising a base plate having a recess therein, a character forming die detachably fitted in said recess, an openable and closable mold body supported upon said base plate, and forming a mold chamber having a series of angularly related sides each provided with a recess, dies mounted in 120 said recesses, and an openable and closable cover for the mold body.
- 125 8. A mold comprising a base plate, an openable and closable mold body mounted upon the base plate and forming a mold chamber having a series of angularly re- 130

lated sides, each provided with a recess, an openable and closable cover for the mold body, and dies adapted to be slidably inserted in and removed from said recesses 5 when said mold cover is opened.

9. A mold comprising a base plate having a recess, a character forming die detachably fitted in said recess, an openable and closable mold body mounted upon the base plate and 10 forming a die chamber having a series of angularly related sides, each provided with

a recess, character molding dies detachably mounted in said recesses, and an openable and closable cover for the mold, the described portions of the mold having surfaces 15 for forming weakened lines in a glass article produced in the mold marginally bounding portions of the glass formed by the die surfaces.

In testimony whereof I affix my signature.

JOSIAH H. WILLIAMS.
